FREDERICK HURST LANSDELL, OF ATLANTA, GEORGIA.

TIMING DEVICE FOR EXPLOSION-ENGINES.

1,165,610.

Specification of Letters Patent.

Patented Dec. 28, 1915.

Application filed December 31, 1914. Serial No. 879,916.

To all whom it may concern:

Be it known that I, FREDERICK H. LANSDELL, a citizen of the United States, residing at Atlanta, in the county of Fulton and State of Georgia, have invented a new and useful Timing Device for Explosion-Engines, of which the following is a specification.

This invention has reference to timing devices for explosion engines and is designed more particularly for multi-cylinder engines, especially the engine employed upon the Ford automobile, although features of the invention are applicable to use in connection with other makes of automobiles, or even with engines employed in other relations than upon automobiles.

The present invention utilizes certain features found in the timing device of the Ford automobile, but by certain changes and modifications of structure some defects in such type of timing device are eliminated.

In the type of timing device referred to a collector is mounted upon the cam shaft 25 of the engine and rotates with it. In the path of this collector is a series of contacts in number corresponding to the number of cylinders of the engine, and these contacts are mounted upon a rockable member by 30 means of which the time of contact is regulated, that is, the arrangement is such that the spark is advanced or retarded after the usual custom. The rockable member has its contacts connected to electric conductors 35 controlling the spark plugs of the engine, and these conductors participate in the rocking movements of the rock member carrying the contacts in the path of the collector on the cam shaft.

40 Experience has shown that repeated operations of the rockable member have the effect of ultimately damaging and often-times breaking the conductors where they are connected to the rockable member, thus 45 producing various engine troubles.

With the present invention the rockable member with its contacts is retained, but is so arranged that it rocks in a seat or holder in which it snugly yet freely moves, and 50 such seat and member may readily be united in a dustproof manner, thus protecting the moving parts of the timer from the deleterious effects of dust and dirt. From the rockable member with its contacts the current 55 rent is taken off by other contacts so the

conductors remain stationary and consequently are not subjected to the treatment which is productive of harmful effects in the prevailing type of timing device, especially as employed on the Ford automobile. Moreover, the electrical connections between the conductors and the rockable member are in the nature of rubbing connections, wherefore the contacts where engaging are always kept bright and the full efficiency of 60 the current is obtained, with corresponding efficiency in the effect of the current at the spark plugs.

The invention will be best understood from a consideration of the following detailed description taken in connection with the accompanying drawings forming a part of this specification, with the further understanding that while the drawings show a practical form of the invention, the latter 70 is not confined to any strict conformity with the showing of the drawings, but may be changed and modified so long as such changes and modifications mark no material departure from the salient features of the 75 invention.

In the drawings: Figure 1 is a front elevation of the improved timer and also showing a small portion of the front plate of the engine to which it is applied. Fig. 85 2 is a vertical section back of the face of the timer as seen in Fig. 1. Fig. 3 is a section on the line 3-3 of Fig. 2. Fig. 4 is a rear elevation of the rockable member. Fig. 5 is a detail section through one of the 90 yieldable contacts. Fig. 6 is a perspective view of one of the elongated plates carried by the rockable member. Fig. 7 is a perspective view of one of the series of contacts carried by the rockable member for engagement by the collector mounted on the cam shaft.

Referring to the drawings there is shown a portion 1 of the engine head usually found on the engine of the Ford automobile, and there is also shown a small portion of the cam shaft 2 of the engine extended through the head 1. Mounted on the cam shaft is the customary spring-urged collecting roller 3 running on the inner periphery of an insulating ring 4 where it engages in order contact blocks 5 embedded in the ring 4. This ring 4 with its circular series of contact blocks is carried by the cylindrical portion 6 of a conical shell 7 held in position by a 100 105 110

spring arm 8 pivotally mounted on the engine head 1 by a bolt 9. The shell 7 is provided with an arm 10 to which is connected a link or reach rod 11 carried to some 5 convenient point of manipulation.

So far the parts described are found in the Ford automobile and constitute parts of the timing device such as is commonly used upon the Ford automobile.

10 The shell 7 of the timing device is so mounted in the Ford automobile as to be capable of rocking movements to vary the time of engagement of the contact roller 3 with the contacts 5 with respect to the 15 movements of the engine pistons to advance or retard the spark in the well known manner. In the timer of the Ford automobile the blocks 5 are each provided with a stem 12 carried through the cylindrical wall 6 20 to the exterior of the shell or casing 7 and there the stems terminate in binding posts by means of which conductors are connected and led away. These conductors participate in the rocking movements of the timing 25 shell or casing 7 constituting the adjustable commutator of the timer, and as this commutator is frequently rocked the conductors are put under more or less bending strain and sometimes break either completely or 30 in part and cause corresponding trouble in the working of the engine. The present invention contemplates a remedy for this troublesome condition by a rearrangement and modification of the parts with some 35 additional features.

Applied to the cylindrical portion 6 exterior thereto is a collar 13 of insulating material, preferably vulcanized fiber, which collar has at the end toward the conical portion of the shell a substantially radial flange 14. The stems 12 of the contact blocks 5 are continued through the collar 13 and are there threaded as shown at 15 to each receive a nut 16. Applied to the exterior of the collar 13 are elongated contact plates 17 conforming to the curvature of the exterior of the collar, and each of a length somewhat shorter than a quarter of the circumferential length of the collar. 40 Each stem 12 traverses a corresponding contact plate 17 near one end of the latter, and the nut 16 serves to hold the contact plate snugly to the collar. The plate can not turn on the stem because lodged against the flange 14. That long edge of each plate 17 remote from the flange 14 is beveled as indicated at 18, and the corresponding edge of the collar 13 is similarly beveled as shown 45 at 19 for a purpose which will presently appear.

Exterior to the collar 13 there is provided a ring or circular yoke 20 preferably of insulating material such as vulcanized fiber. This ring yoke 20 is secured to the engine 50 head 1 on the outer face thereof concentric

with the shaft 2 by clips 21, each made fast at one end to the yoke by screws 22 or otherwise, and at the other end made fast to the plate 1 by bolts 23 which may be the same bolts which ordinarily serve to hold the engine head to the engine. Of course, some other means may be employed for the same purpose, but that described forms a convenient means for securing the ring or yoke 20 in place. This ring carries a series of 70 spring-urged plungers 24 each mounted in a casing 25 embedded in the ring. Each plunger has a stem 26 surrounded by a spring 27 and at the end remote from the plunger 24 extending through a head 28 at 80 the corresponding end of the casing 25. The stem 26 may be headed, as shown at 29, to limit the projection of the plunger 24 from the casing under the action of the spring 27. The plungers 24 constitute 85 yieldable circuit terminals or brushes located to engage the outer faces of the elongated contact plates 17, and these plates are long enough to permit the full rocking movement demanded of the rockable member or commutator of the timing device.

Distributing conductors 30 are each connected to a respective one of the plunger casings 25 by solder or otherwise, and in order to protect the connections the conductors may be carried through appropriate 95 passages 31 in the yoke 20 toward the interior thereof before being connected to the respective casing 25. The outer or face portion of the yoke ring 20 is rabbeted or channeled, as shown at 32, to receive the flange 14 of the collar 13. 100

The commutator or rockable portion of the timer is introduced into the ring 20 and the then inner edge of the collar 13 first engages the plungers 24 spaced about the ring at substantially ninety degrees apart. The continued entering movement of the commutator causes a retraction of the plungers in opposition to the springs 27, this being facilitated by the beveled portions 19 and 18 of the collar 13 and plates 17. When the commutator is fully seated with its inner edge within and guided by an annular rib 33 on the outer face of the 110 head 1, the plungers 24 all bear upon the outer faces of the plates 17 being urged thereagainst by the expansive force of the springs 27 now under greater compression 115 than before the commutator was introduced. When the commutator is fully seated the flange 14 is lodged in the rabbet 32 which is of annular form and, with the fit of the parts close, the flange seals in the working 120 parts of the commutator against accession 125 of dust, dirt or moisture thereto. Since the plungers 24 bear with considerable force upon the plates 17 there is always good rubbing contact with the maintenance of bright surfaces and efficient conducting conditions. 130

The introduction of the moving parts in the circuits, therefore, adds no material resistance.

The conductors leading from the commutator have no parts of them subjected to movement, and, therefore, there is no liability of damage or breakage. Consequently the efficiency of the conductors is not at all affected either by weakening or by final breakage, and troubles which have heretofore been encountered are entirely eliminated. In no instance is there the possibility of weakening the carrying capacity of the conductors by breakage of the strands there-
of or the cutting out of one or more cylinders by a complete breakage of the entire conductor or conductors. Furthermore, the necessity of the installation of new cables which sometimes occurs with the prevailing system because of the shortening of the separate conductors due to breakage to an extent forbidding their further use, is entirely avoided by the present invention, since there is no cause for the breakage of conductors.

The yoke 20 is reinforced and prevented from warping by a metal ring 34 on the face toward the head 1 and heat conduction from the plate 1 through this metal ring is prevented to a suitable extent by another ring 35 of asbestos or other suitable heat insulating material interposed between the ring 34 and the yoke 20.

The spring arm 8 may be moved to one side or the other on its securing bolt 9 as a pivot, and at the free end is formed with a projection 36 entering a socket 37 in the apex of the conical part of the casing 7 in line with the axis of the shaft 2, so that the commutator portion of the timer may be rocked on such axis with which the flange 14 and its seat 32 in the yoke 20 are concentric.

The timer as described provides a means whereby the vehicle is rendered thief-proof, since it is only necessary to swing the spring arm 8 to one side to remove the commutator, but because of the difference in construction and inadaptability of the parts to each other a regular Ford commutator cannot be substituted; so that neither a thief nor a mechanic can then move the vehicle by its own power.

While certain parts of the structure have been described as made of insulating material like vulcanized fiber, it will be understood that any appropriate insulating material other than vulcanized fiber may be used, and also that metal may be employed in place of insulating material with the electrical parts suitably insulated. For instance, it is entirely feasible to make the flange 14 and yoke 20 of metal instead of vulcanized fiber or like insulating material with such parts as the contact parts 17 and plungers 24 with their carriers suitably insulated from the flange and yoke, respectively.

With the present structure the elastic arm 8 constitutes the sole means for holding the rockable member or commutator in its seat in the yoke 20, so that the commutator is readily removed by the simple expedient of 70 swinging the arm 8 to one side thereof, thus releasing the commutator so that it may be lifted away from the yoke.

What is claimed is:—

1. A timer structure for multi-cylinder 75 explosion engines, comprising a rotatable contact, a circular series of relatively fixed contacts, and an intermediately located series of bridging contacts between the rotary and fixed contacts and provided with a 80 mounting rockable to vary the time of completion of the circuits with respect to the movements of the engine pistons, said rockable mounting including a cover portion 85 enclosing the contacting parts of the bridging contacts and the contacts with which they coact, and said rockable mounting being readily removable as a whole from the remainder of the timer structure.

2. A timer structure for multi-cylinder 90 explosion engines comprising a rotatable contact, a circular series of relatively fixed contacts arranged about and spaced from the rotatable contact and provided with a mounting supporting them, and an intermediately located series of bridging contacts between the rotatable and fixed contacts and provided with a mounting rotatable to vary the time of completion of the circuits with respect to the movements of 100 the engine pistons, said rockable mounting including a cover portion having a spread to include all the contacts, the mounting for the fixed contacts being provided with a seat for the cover portion of the rockable member and said rockable member being insertible into and removable as a whole from its seat.

3. A timer structure for multi-cylinder 110 explosion engines, comprising a rotatable contact, a series of relatively fixed and radially yieldable contacts surrounding and spaced from the rotatable contact and provided with a mounting supporting them, and a rockable mounting interposed between 115 the rotatable contact and the radially yieldable contacts and provided with a circular series of bridging contacts corresponding in number to the relatively fixed yieldable contacts, the mounting carrying the yieldable 120 contacts being formed with a seat for the rockable member into which the latter is readily insertible and from which it is readily removable as a whole.

4. A timer structure for multi-cylinder 125 explosion engines, comprising a rotatable contact, a circular series of radially yieldable contacts concentric with and spaced from the rotatable contact and provided with a mounting carrying them, and a rockable 130

mounting located between the rotatable and radially yieldable contacts and provided with a circular series of bridging contacts each having one end in the path of the rotatable contact and circumferentially elongated at the other end to maintain engagement with the radially yieldable contacts during the rocking movements of the rockable member, the mounting for the yieldable contacts being provided with a seat for the reception of the rockable member and the circumferentially elongated ends of the bridging contacts being beveled on the edges first engaging the yieldable contacts on being introduced into the first-named mounting.

5. A timer structure for multi-cylinder explosion engines comprising a rotatable contact, a circular series of radially yieldable contacts concentric with and spaced from the rotatable contact and provided with a mounting carrying them, and a rockable mounting located between the rotatable and radially yieldable contacts and provided 20 with a circular series of bridging contacts each having one end in the path of the rotatable contact and circumferentially elongated at the other end to maintain engagement with the radially yieldable contacts 25 during the rocking movements of the rockable member, the mounting for the yieldable contacts being provided with a seat for the reception of the rockable member and the circumferentially elongated ends of the bridging contacts being beveled on the edges 30 first engaging the yieldable contacts on being introduced into the first-named mounting, said rockable member being also provided with a cover portion having a spread 35 sufficient to cover all the contacts and fit to the seat of the first-named mounting to form a dust guard.

6. A timer structure for multi-cylinder explosion engines comprising a rotatable contact, a circular series of relatively fixed radially yieldable contacts concentric with the first-named contact and spaced therefrom, said radially yieldable contacts being provided with a mounting in the form of a 45 ring-shaped yoke provided with a circular rabbet about its inner periphery, and a rockable member in the form of a shell covering the rotatable contact and provided with a marginal radial flange adapted to the rabbet in the ring-shaped yoke, said rockable member having bridging contacts each with 50 one end in the path of the rotatable contact and the other end circumferentially elongated and in engagement with a respective 55 one of the radially yieldable contacts.

7. A timer structure for multi-cylinder

explosion engines, comprising a rotatable contact, a circular series of relatively fixed radially yieldable contacts concentric with the first-named contact and spaced therefrom, said radially yieldable contacts being provided with a mounting in the form of a ring-shaped yoke provided with a circular rabbet about its inner periphery, and a rockable member in the form of a shell covering the rotatable contact and provided with a marginal radial flange adapted to the rabbet in the ring-shaped yoke, said rockable member having bridging contacts each with one end in the path of the rotatable contact and the other end circumferentially elongated and in engagement with a respective one of the radially yieldable contacts, and a yieldable pivoted holding arm for engaging the axial portion of the rockable member to hold it to its seat in the yoke ring and movable out of the path thereof for the bodily removal of the rockable member from the remainder of the timer structure.

8. A timer structure for multi-cylinder explosion engines comprising a rotatable contact, a rockable member in the form of a shell provided with inner and outer rings of insulating material concentric with the axis of rotation of the rotatable member, said rockable member also having a peripherally expanded marginal flange and a circular series of bridging contacts each with an inner end in the path of the rotatable contact and an outer end circumferentially elongated exterior to the outer insulated ring and electrically connected with the inner end of the bridging contact, and a surrounding ring-shaped yoke of a size 90 to receive the rotatable member where carrying the circumferentially elongated contacts, said yoke having a circular series of radially yieldable contacts each comprising a spring-pressed plunger in position to engage the circumferentially elongated end of a respective bridging contact, the plungers being adapted to be connected with distributing conductors and the ring-shaped yoke having a circular seat for the radial flange of the rotatable member, and an axial holding means for the rotatable member for retaining it in its seat and movable out of the path of the rotatable member to release it for bodily removal from the yoke.

In testimony, that I claim the foregoing as my own, I have hereto affixed my signature in the presence of two witnesses.

FREDERICK HURST LANSDELL.
